UNITED STATES PATENT OFFICE.

CHARLES T. JEFFRIES, OF PHILADELPHIA, PENNSYLVANIA.

RAILWAY-CAR.

SPECIFICATION forming part of Letters Patent No. 237,022, dated January 25, 1881.

Application filed August 9, 1880. (No model.)

To all whom it may concern:

Be it known that I, CHARLES T. JEFFRIES, a citizen of the United States, residing in Philadelphia, Pennsylvania, have invented 5 certain Improvements in Railway-Cars, of which the following is a specification.

The object of my invention is to so construct a railroad-car that it can be readily changed from a day-car to a sleeping-car with substantial and effectively isolated berth-sections. This object I attain in a manner too fully set forth in the following detailed description to need any extended mention in this part of the specification.

15 In the accompanying drawings, Figure 1, Sheet 1, is a longitudinal section of part of the body of a railroad-car constructed according to my invention, and showing the seats arranged for day use; Fig. 2, a view, partly in section, 20 showing the arrangement of sleeping-berths; Fig. 3, Sheet 2, a transverse section of the body of the car, one side showing the seats for day use and the other side showing the sleeping-berths; and Fig. 4, a sectional plan of 25 Fig. 1 on the line 1 2.

A A are the opposite sides of the car-body, provided with the usual windows, and B B are the seats. Each half of the car—that is to say, the space between the sides A and the 30 central passage, D—is separated by permanent partitions E between the seats into a series of sections or compartments, F, each containing two seats, B, adapted during the day for the accommodation of four passengers.

35 The backs G of the seats B are hinged at their lower edges to the seat-frames, and the rear of each back is hollow for the reception of a mattress, a.

To the opposite sides of each partition E, 40 at a point midway between the seat B and the top of the partition, are hinged frames J, also made hollow for the reception of mattresses a, the length of each frame J being equal to half the width of the section or compartment F.

45 During the day the seat-backs G and frames J are elevated and rest against the partition E, being retained in this position by any suitable appliances—turn-buckles, for instance, as shown in Figs. 3 and 4. When turned up in 50 this manner the edges of the frames J and seat-backs G are hidden from view by the stand-

ards d, Fig. 4, with which the ends of the partitions adjacent to the passage D are provided, said standards being of the necessary width for this purpose.

At night the seats B are removed from the seat-frames and placed on the floor between said frames, as shown in Fig. 2, and the seat-backs G and frames J are turned down, as shown by the dotted lines in Fig. 1, the seat-backs, with their mattresses a, thus forming the lower berth, and the frames J, with their mattresses a, forming the upper berth.

The seat-backs G, when turned down to form a berth, are supported by the seat-frames 65 and by lugs e on the sides A of the car-body, the frames J being supported by lugs e and by jointed links f, connected to the fronts of the frames and to the standards d or to the partitions E, as shown in Figs. 2 and 3, the links 70 folding together as the frames J are turned up, (see Fig. 2,) and occupying recesses on the standards d.

The adjacent ends of the seat-backs G and frames J, when said backs and frames are 75 turned down to form berths, are locked by means of bolts g, whereby, in addition to the supporting devices, the necessary security is imparted to the berths. The front of each section or compartment F may be provided 80 with doors or curtains.

It will be noticed, on reference to Fig. 3, that the partitions E do not extend to the roof of the car, the latter being shown by dotted lines, so that, while I am enabled to avail myself of the advantages of permanent partitions between the berths as regards safety and privacy, there is an unobstructed space from end to end of the car above the berths for purposes of ventilation. This space may, 90 if desired, be provided with a grating of wire, or like material, which will effectually prevent communication from one berth to another above the partitions, yet will not interfere with the free passage of air for purposes 95 of ventilation.

The partitions being permanent and the seat-backs G and frames J rigid, the berths are necessarily more substantial than those in which temporary partitions only separate the 100 berths; and the improved car can be rapidly changed from a day-car into a sleeping-car, as

the only operations to be performed are the removal of the seats B, the turning down of the seat-backs G and frames J, and the application of the bed-clothing, the mattresses being already in position when said seat-backs and frames are adjusted.

I claim as my invention—

1. The combination of the permanent partitions E with seat-backs G and frames J, hinged at their lower edges, as described, and each having a recessed back containing a mattress, a, which, when the backs and frames are elevated, rest against the partitions, and when said backs and frames are lowered form respectively the lower and upper couches of the compartment, as set forth.

2. The combination, in a railroad-car, of permanent partitions between the seats and ex-

tending from the central passage or aisle to the car side and from the seat frames or floor to, or almost to, the roof, seat-backs or frames J, or both, hinged so as to be turned down to form berths at night or turned up against the partitions during the day, and standard d on the aisle ends of the partitions, whereby the edges of the seat backs or frames are concealed from view, when said backs or frames are turned up, as set forth.

In testimony whereof I have signed my name to this specification in the presence of two subscribing witnesses.

CHAS. T. JEFFRIES.
